UNITED STATES PATENT OFFICE.

EDWARD B. ALLEN, OF PORTLAND, MAINE, ASSIGNOR TO JAMES W. BROOKS,
TRUSTEE, OF CAMBRIDGE, MASSACHUSETTS.

NAILING-MACHINE FOR BOOTS AND SHOES.

SPECIFICATION forming part of Letters Patent No. 332,032, dated December 8, 1885.

Application filed November 24, 1884. Serial No. 148,666. (No model.)

To all whom it may concern:

Be it known that I, EDWARD B. ALLEN, of Portland, county of Cumberland, State of Maine, have invented an Improvement in 5 Heeling-Machines for Boots and Shoes, of which the following description, in connection with the accompanying drawings, is a specification, like letters on the drawings representing like parts.

10 This invention relates to that class of heeling-machine known in the market as the "McKay & Bigelow," it being substantially represented in United States Patent No. 203,440, dated May 7, 1878, and has for its object improvements in mechanism for automatically placing the top lift in position, and also to improvements in mechanism for controlling the movements of the nailing and of the trimming devices. In another application filed 15 by me for United States Patent, Serial No. 130,242, I have shown and described a mechanism for automatically presenting a top lift in place, and the mechanism herein shown is intended as an improvement thereon. The 20 same application, and also a second application, Serial No. 130,341, shows and describes mechanism for automatically operating the top-lift plate, and it will be understood that in practice the machine herein described will be provided with a top-lift-plate-moving mechanism, substantially such as 25 therein described. To avoid the delay occasioned in actuating these several treadles in their order by the operator, and to make the machine automatic in its operations from the 30 time the heel is to be nailed to the shoe until the heel is trimmed and released, I have reorganized the said machine and provided it with mechanism under the control of but one 35 treadle, one movement of which by the operator will engage a clutch to start the machine, raise the die-bed spindle to clamp the heel against the shoe, and thereafter certain cams and devices under their control will keep the 40 said clutch in engagement, and also effect the engagement at the proper time of the clutch to start the trimming mechanism, and the top lift having been added, and the heel having been trimmed and its mechanism restored to 45 its starting-point, the die-bed spindle will be automatically lowered and all the clutches disengaged.

Figure 1 is a left-hand side elevation of a

machine of the class referred to embodying my improvement, the parts being in position 55 to lift the die-bed spindle to attach the top lift; Fig. 2, an enlarged detail of part of the top-lift carrier. Fig. 3 is a section of Fig. 2 in the dotted line x x . Fig. 4 is a right-hand side elevation of the lower part of the machine 60 shown in Fig. 1. Fig. 5 is a vertical central section of Fig. 4. Fig. 6 is a horizontal section in the line x^3 x^3 , Fig. 5. Fig. 7 is a detail to be referred to; and Fig. 8, a detail of the track for moving the latch, to be described.

The frame-work of the machine, shaft a , driving-pulley b , shaft e , having the crank or projection i , gear d thereon, the walking-beam n^2 , rod p^2 , link s^2 , shaft t^2 , cam-plate u^2 , link x^2 , 70 lever y^2 , the working screw-spindle f^2 , the die-bed spindle l , the toggle-lever k , the trimming-lever a^2 , the carriage r , its guide-rail s , and the chain o , sheaves n and p , lever f , knock-off cam x , the trimming-shaft g , its crank 14, to move 75 the lever a^2 , the gear 7, loose on the shaft g , the ratchet 9, the weighted arm 10, fast on the shaft g , the pawl 11, the short arm 12, the spring-pressed pin 13, rod c^2 , pawl-holding device b^2 , elbow-lever 24, link 23, to move it to slide the 80 rod c^2 , and stop-pin 28, are all substantially as in the patent referred to, wherein like letters are employed to indicate like parts, it being, however, noted that the rod c^2 is shortened, and that some parts heretofore connected with it 85 have been omitted, and it will also be observed that the devices for moving the walking-beam and operating the link 23 are somewhat altered, as will be described.

The carriage D or jack employed in connection with the spindle f^2 , to hold and adjust the shoe B while the heel is nailed to it and while the heel is being trimmed, and the nail-driving mechanism H^2 and heel-trimming mechanism H , both deriving their movement from the 95 die-bed spindle l and the lever a^2 , respectively, are all substantially as in the well-known McKay & Bigelow machine referred to, and hence need not be herein further described. The said devices are, however, referred to and 100 described in the United States Patent No. 203,440. The nail-box A , which contains the usual nail drivers, and has at its top a pivoted top-lift plate, is the same as that referred to by like letter in my application Serial No. 105 130,241, the said nail-box and top-lift plate

being also common to the United States Patent No. 166,795, dated August 17, 1875. The top-lift carrier (shown best in Fig. 2) is composed of a head, a^3 , made vertically adjustable 5 in a block, b^3 , adjustably attached by a set-screw, c^3 , to an arm, d^3 , of a slide-rod, e^3 , preferably made square or angular, to obviate rotation thereof, the said slide-rod having its 10 bearings in guides fixed to the frame. The head is provided with levers or arms g^3 , pivoted at g^4 , the said arms having pivoted in turn upon them the top-lift clamps h^3 , which are preferably serrated, as shown, and concaved to grasp the edges of the top lift, i^3 . 15 The clamps are normally kept pressed against the top lift by suitable springs, k^3 , preferably made adjustable by screws m^3 . The rear end of the top lift is acted upon by a concaved dog, n^3 , pivoted upon a slide, o^3 , which, when the dog 20 is brought to a point to insure the proper position for the top lift with relation to the top-lift plate (not shown) at the top of the nail-box, is secured in place by the set-screw p^3 . The slide-rod e^3 , referred to, has a pin, r^3 , extended laterally from it which is embraced 25 by the forked lower end of the lever s^3 , pivoted at t^3 , the said lever being vibrated by and locking the connecting-lever u^3 , pivoted at its rear end to the rod p^2 , the lever s^3 and rod e^3 30 being moved forward to place a top lift in position when the spindle f^2 is lifted, the joint between the rod p^2 and lever s^2 , being at such time broken or sprung, as in Fig. 1, wherein the top-lift carrier is represented as moved 35 forward to place a top lift in proper position to be "blinded" upon the projecting nails of the attached heel when the die-bed spindle is next raised.

To return the rod e^3 and its attached top-lift carrier, the carriage r has been provided 40 with a latch, b^4 , pivoted thereon at b^5 , and provided with a shoe, b^7 , which is normally kept pressed toward the track b^8 , provided with an incline at b^9 . The upper end of the 45 latch b^4 is provided with a plate, c^4 , which comes against the pin r^3 , and, acting against it, carries the rod e^3 back with it; but just before the plate strikes the said pin the end of the said plate also strikes the lower end of the connecting-lever u^3 , lifting it so that the 50 upturned or angular end of the slot c^5 therein is lifted from the pin c^6 in the lever s^3 , thus releasing the said lever, so that it can be carried back with the rod e^3 through the action 55 of the pin r^3 . The lever u^3 , slotted and co-operating with the pin c^6 , forms a locking device to retain the top-lift carrier forward. After 60 the locking device has been lifted, as stated, the pin c^6 , during the backward movement of the rod e^3 , is made to travel in the slot c^5 , and thereafter, when the rod p^2 is moved back by the lever s^2 in the direction of the arrow 100 thereon, Fig. 1, the lever u^3 is drawn back, and its slotted part c^5 rides on the pin c^6 , until the bent or angular part of the slot reaches the said pin, when the lever u^3 drops, and it and the lever s^3 become again locked together,

so that as the rod p^2 is again moved in the opposite direction the rod e^3 and top-lift carrier will be moved forward positively. The 70 rod e^3 cannot, however, be so moved forward until after the latch b^4 is released from contact with the pin r^3 . This release is effected by the latch striking against the incline b^9 of the track s . The lever y^2 derives its motion 75 from the rod w^3 , provided with a shoulder, y^1 , and extended through an eye in the pin or bolt a^4 , which connects the die-bed spindle with the toggle k , a spring, a^5 , placed on the said rod below the bolt a^4 , being retained in place by the nuts a^6 . This connecting-rod is not of my invention, and is not herein claimed. The lever f , connected with the pin which joins the upper and lower members of the toggle k , is lifted into engagement with the crank i , 85 which straightens the toggle by a crank, d^3 , on a shaft, d^4 , provided with a toothed gear, d^6 , running loosely thereon, the said gear being engaged and driven by a pinion, d^5 , fast on the shaft e . The gear d^6 has its hub at its 90 outer side provided with a tooth, d^7 . The shaft d^4 has fast on it, outside the gear d^6 , an arm, d^8 , provided with a pivoted dog, d^9 , acted upon by a spring-pressed pin, d^{10} , the latter acting to keep one end of the said dog in contact with the tooth d^7 , and at such time insure the rotation of the gear d^6 in unison with the shaft d^4 , the said arm, dog, and tooth constituting a clutch, the dog being held out from engagement with the tooth d^7 , until the machine is to 95 be started, by means of the shoe e^4 , secured to an arm, e^5 , attached by set-screws e^6 to a slide-pin, e^7 , fitted into a fixed box, e^8 . The arm e^5 is guided between its ends by a fixed guide, e^9 , made as a round rod, a spring, e^{10} , being interposed between the said arm and the head of the rod, as in Fig. 6, to normally keep the said arm pressed in toward the side of the frame. When the treadle f^4 is depressed, its lower side strikes the elbow-lever f^5 , pivoted 100 at f^6 , and turns the latter, causing it to act against the lug f^7 , forming part of the arm e^5 , thus moving the said arm outward or away from the side of the frame, removing the shoe e^4 , attached to the arm e^5 , from contact with 105 the end of the dog d^9 , which results in enabling the pin d^{10} , placed in a guide on the arm d^8 and surrounded by a spring, (not shown,) to turn the said dog and effect the engagement of its opposite end with the tooth d^7 of the hub of the gear d^6 , which will cause the rotation of the shaft d^4 with the said gear d^6 , the crank d^3 of the shaft d^4 lifting the lever f into 110 position to be struck by the crank i on the rotating shaft e , the said lever, when moved by 115 the crank i , straightening the toggle and lifting the die-bed spindle to drive the nails which attach the heel to the shoe, such movement being accomplished through a partial rotation of the gear d^6 . The nails having been driven, 120 the toggle is at once broken or sprung by the action of the trip-cam x on the projection m (see dotted lines, Fig. 4,) of the lever f . The cam x , as herein shown, is mounted on a stud, 125

g⁴, having an attached arm, g⁵, which is moved at the proper time by the eccentric g⁷ on shaft d⁴ through the connecting-rod g⁶. While the die-bed spindle l is momentarily lowered, the 5 top-lift carrier is actuated to place the top lift in place above the top-lift plate of the nail-box, preparatory to again lifting the said spindle. The top lift having been carried into position to be blinded upon the ends of the nails, the 10 crank d³, in the continued rotation of the gear d⁶, again strikes the lever f and lifts it until the crank i again strikes the shoulder 80 thereof and straightens the toggle and lifts the die-bed spindle. The shaft d⁴ has fast upon it 15 within the frame a pinion, g⁸, which engages a cam-gear, g⁹, mounted on a stud, g¹⁰, connected by a set-screw (see Fig. 6) with a sleeve-like part of the fixed box e³. The cam-gear g⁹, twice the diameter of the pinion g⁸, has at 20 its outer side a cam, h⁴, (see Fig. 7,) which at the proper time acts upon the roller or other suitable end, h⁵, of the slide-rod e⁷, referred to, the said cam acting on the said slide-rod serving to retain the shoe e⁴ in position to maintain 25 the engagement of the dog d⁹ with the tooth d⁷ and continue the rotation of the shaft d⁴ until the cam-gear g⁹ has completed a rotation. This cam-gear has at its inner side, nearest the center of the frame, a cam, h⁶, 30 which at the proper time strikes the rod h⁷, carried by arms h⁸ on the rod h⁹, the latter being jointed by link h¹⁰ to the lower end of the lever 23, the latter, when moved through the medium of the said cam, actuating the 35 shoe b² in the direction to effect the engagement of the dog 11 with the ratchet 9, to start the shaft 8 and its crank 14 and cause the vibration of the lever a², which operates the heel-trimming mechanism in the usual manner. 40 The rod h⁹ is kept pressed toward the gear g⁹ by the spring k⁴, and as soon as the cam h⁶ passes beyond the roll h⁷ the lever 23 is moved by the spring k⁴ back into its normal position, thus placing the shoe b² in position to 45 strike the dog 11 to effect its release from the ratchet 9 when the rotation of the shaft 8 is stopped, as usual. Just after the usual knife of the heel-trimming mechanism has completed its work a pin or projection, k⁵, strikes 50 the upper end of the lever h⁶, pivoted at k⁷, and moves the latter, so that its lower end, then in contact with the pin k⁸ of the lever f, it being understood that the toggle is yet straight, moves the said lever f to effect the breaking 55 or springing of the toggle k, which springing was previously accomplished by the cam x. Immediately after starting the shaft 8, as described, the cam h⁴ of the gear g⁹ passes beyond the roll h⁷ and permits the slide-rod e⁷ and 60 its arm and shoe e⁴ to be moved by the spring e¹⁰, to place the shoe in its normal position and insure the disengagement of the dog d⁹ from the tooth d⁷ and stop the shaft d⁴, the lever f⁵, during such movement, acting to lift the 65 treadle.

I do not desire to limit my invention to the exact devices shown between the cam-gear g⁹

and the shoe b², to effect the movement of the latter, nor to the exact devices shown to effect from the said cam-gear that movement of the 70 shoe e⁴ which maintains the engagement of the dog d⁹ with the tooth d⁷ for more than one full rotation of the shaft d⁴, and then permits the movement of the said shoe to effect the disengagement of the dog d⁹ from the said 75 tooth d⁷, for it will be understood that other equivalent devices might be employed. The shaft e, its attached gear d, pinion d⁵, gear d⁶, and the gear 7, loose on the shaft 8, and driven from the shaft a, as is also the gear 80 d, are rotated continuously, and these gears, through the dogs and shoes described, are caused to operate the shaft d⁴ and the shaft 8 at the proper times to effect the operation of the die-bed spindle and trimming mechanism 85 in the necessary order, and it will be noticed that the movements of all the parts, to attach a heel to a boot or shoe, apply the top lift, and then trim the heel, are all effected by one single treadle. 90

The frame-work of the machine is designated W.

I claim—

1. The top-lift carrier and its slide-rod, combined with the lever s³, to engage and 95 move the said rod and carrier forward, substantially as described.

2. The top-lift carrier and its slide-rod, and the lever s³, combined with the connecting and locking lever, and with means to actuate the 100 same at the proper times, substantially as described.

3. The top-lift carrier, its slide-rod and pin r³, and lever s³ and means to operate it, combined with the latch and the carriage on 105 which the same is mounted, the latch causing the backward movement of the slide-rod, substantially as described.

4. The top-lift carrier, its slide-rod and pin r³, and lever s³ and means to operate it, 110 and the latch and the carriage r, on which the same is mounted, the latch causing the backward movement of the slide-rod, combined with the track b⁸, having the incline to operate the latch, substantially as described. 115

5. In a heel-ing-machine, the arm e³, the shoe e⁴, and the rod e⁷, combined with a cam-gear and a treadle to control the position of the said shoe, substantially as described.

6. The die-bed spindle, its toggle k, and the lever f, combined with the trip-cam and with the lever k⁶, and adapted to be operated in succession, as described, to break or spring the said toggle, substantially as described. 120

7. In a heel-ing-machine, the shaft 8, and pin or projection moved thereby, and lever k⁶, combined with the lever f, its connected toggle, and the die-bed spindle, substantially as described. 125

8. In a heel-ing-machine, the die-bed spindle, the toggle, the lever f and cam x, and the shaft d⁴, combined with the rod g⁶, to operate substantially as described. 130

9. In a heel-ing-machine, the positively-ro-

tated gear g^9 , provided with a cam, and the shoe b^2 , combined with intermediate mechanism, substantially as described, to automatically effect the movement of the said shoe to start the shaft 8.

10. In a heelng-machine, the shafts 8 and d^4 , the dogs 11 and d^9 , connected therewith respectively, the shoes b^2 and e^4 , and the continuously-driven loose gears 7 and d^6 , combined 10 with a suitable cam, h^6 , and with means, substantially as described, intermediate the said shoes and cam, to control the movement of the shoes in the proper order, as and for the purposes set forth.

11. In a heelng-machine, the shafts 8 and d^4 , the dogs 11 and d^9 , connected therewith respectively, the shoes b^2 and e^4 , and the continuously-driven loose gears 7 and d^6 , combined 20 with a cam and with means, substantially as described, intermediate the said shoes and cam, to control the movement of the shoes in the proper order, and with a single treadle, as and for the purposes set forth.

12. The shoe-carrying arm e^5 and its guide 25 and slide-rod, combined with the treadle and intermediate lever, f^5 , substantially as described.

13. In a heelng-machine, the top-lift carrier and the die-bed spindle, combined with 30 intermediate connecting mechanism, substantially as described, it consisting of the lever y^2 , moved from the die-bed spindle, joint s^8y^2 , and levers u^3s^3 , to operate the top-lift carrier through the die-bed spindle.

35 14. In a heelng machine, the top-lift carrier, the die-bed spindle, and intermediate mechanism, substantially as described, to actuate the top-lift carrier from the die-bed spindle, combined with a cam and with means, 40 substantially as described, to actuate the said cam and die-bed spindle, the said cam determining the time of the ascent and descent of the said spindle, for the purposes set forth.

15. In a heelng-machine, the die-bed spindle, its toggle, the toggle-moving lever f , the crank or projection i , to actuate the said lever to straighten the toggle, the intermittently-operated shaft d^6 , to lift the lever f , a trip-cam actuated from the said shaft, a loose gear thereon, a clutch, and a shoe to control its engagement and disengagement to start and to stop the said shaft, combined with a treadle to move the said shoe, and with a cam and intermediate mechanism to maintain the said shoe in position to effect two rotations of the said shaft d^4 , substantially as described.

16. The continuously-rotated gear 7, shaft 8, its crank to effect the movement of the trimming mechanism, clutch mechanism between 60 the said shaft and gear, a shoe, b^2 , to effect the engagement and disengagement of the said clutch, the die-bed spindle, its toggle, and connected lever f , and means actuated by the shaft to spring or make the toggle, the continuously-rotating gear d^6 , shaft d^4 , provided 65 with a cam or projection to lift the lever f .

preparatory to straightening the toggle, a clutch to connect the said gear with the said shaft, a shoe, e^4 , to effect the engagement and disengagement of the said clutch, and means 70 to actuate the trip-cam from the shaft d^4 , combined with a treadle to move the shoe e^4 to engage the clutch and rotate shaft d^4 , and with a cam to continue to hold the shoe e^4 in place while the shaft d^4 makes two full rotations, as 75 and for the purposes described.

17. In a machine to attach heels to boots and shoes, and then to automatically trim the same, the clutch mechanism and its shoe b^2 , to control the starting and stopping of the trimming mechanism, and the clutch mechanism to control the starting and stopping of the die-bed spindle, combined with a single treadle to place in position the shoe to engage the latter clutch mechanism, and with cams and mechanism actuated thereby to maintain the said clutch in engagement during the ascent, descent, and second ascent of the die-bed spindle, and to thereafter actuate the shoe b^2 , to engage the clutch, such engagement starting 90 the heel-trimming mechanism, substantially as described.

18. The die-bed spindle, its connected toggle, and lever f , provided with two projections, combined with means to strike the said projections in succession and automatically move the said lever in the direction to spring or break the said toggle and lower the die-bed spindle preparatory to blinding the top lift on the heel and to release the trimmed heel, 100 as described.

19. The die-bed spindle, its toggle, and connected lever f , and the shaft e , and its crank or projection to move the said lever to raise the die-bed spindle, combined with the shaft d^4 and a crank or projection actuated thereby to automatically lift the lever f and place it in position to be actuated by the crank or projection of the shaft e .

20. The die-bed spindle, its toggle, and connected lever f , the shaft e , provided with a crank or projection, i , to move the said lever to lift the die-bed spindle, and the shaft d^4 , provided with a crank or projection to lift the said lever f into position to be engaged by the said crank or projection i , combined with a clutch to effect the rotation of the shaft d^4 at the proper time, a shoe, e^4 , to cause the engagement of the said treadle to move the said shoe, and a cam and intermediate devices to hold the said shoe in position, to keep the clutch engaged while the shaft d^4 makes two rotations to thus aid in lifting the die-bed spindle twice in succession, as set forth.

In testimony whereof I have signed my name 125 to this specification in the presence of two subscribing witnesses.

EDWARD B. ALLEN.

Witnesses:

G. W. GREGORY,
Jos. P. LIVERMORE.
